W. G. Hermance,

Automatic Gate,

No. 22,023.

Patented Nov. 9, 1858.

UNITED STATES PATENT OFFICE.

WM. G. HERMANE, OF GENEVA, NEW YORK.

METHOD OF OPENING AND CLOSING FARM-GATES.

Specification of Letters Patent No. 22,023, dated November 9, 1858.

To all whom it may concern:

Be it known that I, WILLIAM G. HERMANE, of the village of Geneva, town of Seneca, county of Ontario, and State of New York, have invented a new and Improved Gate with Appendages, the Design of Which is to Insure the Most Convenient and Economical Means of Passing Into and Out of an Inclosure; and I hereby declare that the following is a full and accurate description thereof, reference being had to the accompanying drawing and the letters of reference thereon.

I construct a frame in the usual manner with posts firmly set in the ground and surmounted by a transverse beam or plate connecting them at top and properly braced as set forth in Figure 1. A A posts; B, B, beams; C, C, braces. I also construct a double gate consisting of two distinct and independent parts represented in the figure at D, D, D, D. These gates I suspend on vibrating beams E, E by means of slats F, F, F, F, firmly fastened to them. In the upper end or head of each slat which is thickened for the purpose I invert in a mortise two pulleys so arranged that the vibrating beams to be described shall be embraced by one of the pulleys above and the other below it, the side of the mortise being so cut away as to allow the free passage of the pulleys past the pins or bolts of the vibrating beams, see Fig. 2, which represents the slat head with mortise and pulleys. The slats just described are of unequal length as seen in Fig. 1, so that when the gates are shut they are level and the heads of the slats are at unequal heights corresponding with their place on the vibrating beams.

The vibrating beams E, E, E, E, are made of this stuff with sufficient strength when placed vertically edgewise to sustain the weight of the gate, and they are secured to the posts as seen at 8, 8 by bolts or pins or other mechanical equivalents so that they shall vibrate freely. On these vibrating beams the gates are always suspended whether in the act of shutting or opening the same.

In the front and rear side of the beam a plate B, B, I insert two opposite arms 9, 9 and on these I build a system of levers, as seen in the figure, for the purpose of raising or depressing the ends of the vibrating beams, which are joined at H and move

freely at the joint, the compound motion of these ends being provided for by a slot in one or both of the beams at the point of junction, through which the pin passes that connects them with the rod I, which in its turn is connected with the levers K L and L by means of a fork with a pin passing through it and working in a slot in the lever so as to allow the compound motion to be effected. The same slotted arrangement is made in the compound levers L and L. When more convenient or necessary I provide for the compound motion of the levers by making a hinge joint at the bottom of each fork and boring a round hole for the pin that is the bracing of the lever, and a double hinge or pair of straps at the ends of the vibrating beams so connecting them with the rod I, as to provide for the compound motion incident to the elevation and depression of the ends of said beams.

At a convenient distance on either side of the gate and within reach of persons on horseback or in a carriage I suspend from the ends of the levers K K and L a rod M or a rope 19 or 15 for the purpose of operating the whole arrangement without leaving the carriage or dismounting from the horse.

The operation of this combination is as follows: A foot passenger may go through the gate by sliding one of its parts aside with his hand on the gate. Persons on horseback or mounted on a wagon or in a carriage by pulling down the arm M by the operation of the lever K raises the rod I and the ends of the vibrating beams E, E, until these ends are higher than the center of the beam, when the gates will slide or roll outward and thus open. It will be seen however in practice that before the gates part at the bottom the tops will be open and the space will be like the letter V. This is owing to the slats being of unequal length and the shortest being innermost after passing through. The gates are shut by pushing up the arm M or its mechanical equivalent or by pulling down the rope N connected with the compound lever, by which the rod I and the inner ends of the vibrating beams E, E, are depressed and the gates roll together.

It will be seen that in the figure there are four posts O O and P P, which may be long or short and connected if necessary with a bar from O to O. They stand at a sufficient distance from the fence or gate posts to al-

low the free passage of the gates between them and the fence or gate posts. They are for the purpose of suitably confining the lower parts of the gates while in motion. 5 The post R with a split head and bumper pin or other mechanical equivalent is to stop each gate at the center and to confine the gates when shut at their proper places.

I do not claim the construction of the 10 gates, beams, braces, levers, arms, or pulleys separately; but

That which I do claim and for which I desire Letters Patent is—

The suspension of the gates by means of suspension bars of unequal length with pul- 15 leys and slat heads arranged as set forth.

In testimony whereof I have hereunto set my hand.

WM. G. HERMANCE.
